[57] **CLAIM**

I claim the ornamental design for a continuous, baseboard style electrical connector, as shown and described.

DESCRIPTION

FIG. 1 is a front, top and side perspective view of the continuous, baseboard style electrical connector embodying the design of the present invention, and is shown with a break to indicate an indeterminate length.

FIG. 2 is a front elevational view thereof.

FIG. 3 is a rear elevational view thereof.

FIG. 4 is a transverse view thereof, taken along line 4—4 in FIG. 2; and,

FIG. 5 is a transverse view thereof, taken along line 5—5 in FIG. 2.

The dot-and-dash lines showing an electrical plug in FIGS. 1 and 5 is included for the purpose of illustrating environmental structure only and forms no part of the claimed design.
